CODED FEEDBACK CIRCUIT FOR RAILWAY
TRAFFIC CONTROLHoward A. Thompson, Edgewood, Pa., assignor to
The Union Switch & Signal Company, Swiss-
vale, Pa., a corporation of Pennsylvania

Application August 18, 1942, Serial No. 455,170

17 Claims. (Cl. 346—38)

My invention relates to coded control circuits for use in systems of railway signaling, and it has special reference to the employment by such circuits of the "coded feed back" operating principle that first was disclosed by Frank H. Nicholson Patent No. 2,021,944 (issued November 26, 1935) and that also is shown by numerous later patents and applications of common ownership herewith.

Generally stated, the object of my invention is to increase the utility and broaden the range of application of "coded feed back" control circuits of both the track and the line type.

A more specific object is to organize the apparatus elements of such circuits in a new and improved manner that is alternative to the organization which Assignee's Patent No. 2,286,002 issued June 9, 1942, to Frank H. Nicholson discloses and claims.

Another object is to provide for such "coded feed back" control circuits a design wherein the "storage potential" plus "bridging contact" protection features of the aforesaid Nicholson form of organization are supplemented by further desirable characteristics not heretofore attainable.

A further object is to render both the "feed back" and the "master code" relays of such circuits highly immune to false operation by "foreign" and "inductive kick back" currents that may be present in the circuit conductors.

A still further object is to provide for direct current track circuits of the "frequency code" signaling system type an improved "feed back" design which permits alternating current energy for cab signal control to be superimposed upon the direct current "master" energy pulses over a supply path which need not include the operating winding of the detector relay.

In practicing my invention I attain the above and other objects and advantages by: (1) using "master code" and "feed back" energy pulses which have an opposing polarity relation in the control circuit conductors; (2) connecting the feed back detector relay to those conductors in multiple (instead of in series) with the master energy source and connecting the master code following relay to those conductors in multiple (instead of in series) with the feed back energy source; and (3) serially including in each of those connections a reactor impedance by which conductor storage energy is prevented from falsely operating the connection-embraced relay.

I shall describe several forms of "coded feed back" control circuits which embody my in-

vention, and shall then point out the novel features thereof in claims. These illustrative embodiments are disclosed in the accompanying drawings in which:

5 Fig. 1 is a diagrammatic representation of a track type of control circuit that incorporates the improvements of my invention and that is organized to form part of an automatic block signaling system having "coded feed back" approach lighting control;

Fig. 2 shows "master" and "feed back" codes which are suitable for use by the circuit of Fig. 1;

Fig. 3 illustrates modified entrance end apparatus for the track circuit of Fig. 1;

15 Fig. 4 represents modified exit end apparatus for the same track circuit;

Fig. 5 shows one of my improved track circuits organized into a "cab signal only" system of automatic block control;

Fig. 6 shows train-carried cab signal apparatus which may be controlled by the trackway equipment of Fig. 5;

Fig. 7 illustrates modified exit end apparatus for the track circuit of Fig. 5;

25 Fig. 8 reproduces the cab signal control track circuit of Figs. 5-7 together with supplements for the further control and approach lighting of wayside signals;

Fig. 9 illustrates modified exit end apparatus for the track circuits of Figs. 1, 5 and 8; and

30 Fig. 10 shows how the improvements of my invention may be utilized in a coded track circuit scheme of controlled manual block signaling.

35 In the several views of the drawings, like reference characters designate corresponding parts. Referring first to Fig. 1, the improved control circuit organization of my invention is there disclosed in association with a coded track circuit system of automatic block signaling for a railway track 1-2 over which it will be assumed that traffic moves in the single direction indicated by the arrow, or from left to right in the diagram. The protected stretch of this track is divided into the customary successive sections by insulated rail joints 3 and the rails of each section form part of a track type of control circuit which normally is capable of transmitting energy between its two ends but which at times is rendered incapable of such transmission.

The basic combination of Fig. 1

In this view of Fig. 1, reference characters II and III respectively designate the entrance 45 and the exit ends of one of these track sections.

This particular section is illustratively shown as being a full signal block in length and its entrance end is guarded by the usual wayside signal SII. Typified by signal SIII at location III is a corresponding device at the entrance end of each of the remaining track blocks in the complete system.

The improved track circuit combination of Fig. 1 is suitable for controlling signal SII and for approach lighting signal SIII without the aid of line wires between signal locations and solely by means of coded energy that is transmitted through the rails of section II-III.

In the form illustrated by Fig. 1, my improved track circuit combination performs these two functions through the utilization of: (1) apparatus at the section exit III comprising a source of "master code" energy TB, a coder relay CR having a contact 5 which recurrently applies energy from this source to the section rails 1-2 and thereby produces the "master code" of Fig. 2, the detector relay KR connected in energy receiving relation with the rails, and an approach relay AR which is controlled by the detector relay; and (2) apparatus at the section entrance II comprising a code following track relay TR operated by the master energy pulses that the rails transmit, a source of "feed back" energy KB, an impulse relay IR having a contact 6 which connects the feed back source with the section rails during each "off" period (see Fig. 2) of the received master code, and decoding apparatus H-D which selects the indication of signal SII in accordance with the rate at which track relay TR follows code.

This rate is, of course, determined by the number of times per minute that the exit end coder relay CR picks up and releases its contact 5. Operation of the coder relay is produced in any one of a number of well-known manners (not shown in Fig. 1) of which devices CT180-CT75-H of Fig. 5 (later to be described) constitute one example. Those elements cause coder relay CR to operate at a high speed or 180 pulse per minute code rate when the section ahead of location III is vacant and at a low speed or 75 pulse per minute code rate when that advance section is occupied.

In either instance, the rails are supplied with master code energy in the form of recurring "on" period pulses that are separated by "off" period intervals. The supply path for each of these pulses extends from the positive terminal of master source TB through a current limiting impedance 8, front contact 5 of device CR, conductors 9-10, the section rails 1 and 2, and conductors 11-12 back to the negative terminal of source TB.

By each of these master code pulses rail 1 is made positive with respect to rail 2 and the pulse polarity will herein be designated by the term of "positive" or "given." In the diagram of Fig. 2, each of the master energy pulses has accordingly been represented on the upper side of the base line.

Under vacant conditions of section II-III, these recurring pulses of master code energy are transmitted to the entrance location II. There, each is impressed upon the operating winding of track relay TR over a path extending from section rail 1 through conductor 14, the winding of relay TR, conductor 15, back contact 6 of device IR and conductors 16-17 back to rail 2.

In the form represented, this track relay TR is of the familiar "polar biased" type the con-

tacts of which pick up only in response to applied winding energy that has the just described normal or positive polarity. Such energy flows current through the relay winding in the direction of from left to right, as shown by the small arrow. Flow of winding current in the opposite direction merely urges the track relay contacts more firmly into their deenergized or released positions.

Looking at the single contact 17 that is represented for relay TR, it picks up in response to each pulse of normal polarity master code that reaches relay TR's winding and releases during each of the "off" period intervals by which the master code pulses are separated. Application of negative or "opposite" polarity energy to the relay winding during those "off" periods is, moreover, ineffective for picking up contact 17.

Through decoding apparatus H-D of well-known character, track relay TR causes its controlled signal SII to show: (1) "clear" when the relay is following master code of the 180 or high speed variety; (2) "approach" when the relay is following master code of the 75 or low speed variety; and (3) "stop" when the relay fails to follow code. For one illustrative form which such decoding apparatus H-D may take, reference may be had to the entrance end portion of Fig. 8 (later to be described).

By the track circuit elements which have just been described the indication of signal SII thus is selected in customary three indication automatic block manner.

Supplementing these signal control elements are "feed back" facilities through the medium of which signal SIII may be approach energized without the aid of line wires. These feed back facilities utilize the earlier named devices KB-IR at entrance location II and the earlier named devices KR-AR at the exit location III.

Under the control of impulse relay IR, the entrance end source KB supplies the section rails with "feed back" energy in the form of pulses that recur in step with the "off" periods of the master code energy which track relay TR receives. In the illustrative form shown, relay IR is of the same polarized type as that shown and described by Herman G. Blosser Reissue Patent No. 21,783. It receives operating energy from a transformer RT in the exciting circuit of which track relay contact 17 operates in well-known pole changing manner.

As long as the winding of this impulse relay IR remains deenergized or receives "reverse" polarity energy, contact 6 stays released and keeps the operating winding of track relay TR bridged directly across the sections rails. This connection is completed during each "on" period of the received master code and has already been traced in detail.

At the beginning of each "off" period of the received master code, the accompanying release of track relay contact 17 causes transformer RT to supply relay IR with a short pulse of "given" polarity energy. This energy flows through relay IR's winding in the direction shown by the small arrow and produces a momentary pick-up on the part of contact 6. By each of these pick-ups, source KB is connected with the section rails and caused to supply a pulse of "feed back" energy thereto.

The supply path for each of these feed back pulses extends from the positive terminal of source KB through a current limiting impedance 19, front contact 6 of device IR, conductors

16—17, section rails 2 and 1, and conductors 14 and 20 back to the negative terminal of source KB. Energy flowing from source KB over the just named connection makes rail 2 positive with respect to rail 1.

This relation being directly opposed to that which results from the earlier described connection of master energy source TB with the section rails, the pulses of "feed back" energy thus have what will be referred to as a "negative" or "opposite" polarity. In Fig. 2, this is shown by feed back pulse representations which are below the base line.

The thus supplied pulses of feed back energy recur in step with the "off" periods of the master code energy by which the track relay TR is operated; each has the relative shortness indicated by Fig. 2 and terminates before the beginning of the succeeding master code "on" period; and in being transmitted to the section exit end III, these feed back pulses are impressed upon the winding of the detector relay KR.

This detector relay is a code following device of the "polar stick" or magnetically toggled type. Flow of current through the relay winding in the direction of from right to left effects a right or reverse positioning of contacts 23—24, while flow of current through the relay winding in the opposite direction effects a left or normal positioning of those contacts. Once, moreover, the contacts reach either of these positions they there remain continuously until the relay winding is energized in the opposing direction.

In the particular connection shown: (1) each positive or "normal" polarity pulse of rail-supplied "master code" energy flows relay current in the first-named direction and thereby operates contacts 23—24 to their right position, as is illustrated in full lines, and (2) each winding received pulse of negative or "opposite" polarity "feed back" energy flows relay winding current in the second-named direction and thereby operates contacts 23—24 to the left, as shown in dotted lines.

The circuit over which such positive polarity "master" rail potential energizes relay KR extends from the positive terminal of source TB through impedance 8, front contact 5 of device CR, conductor 9, a reactor 27, the winding of relay KR and conductor 12 back to the negative terminal of source TB. This energization occurs during each master code "on" period and under both vacant and occupied conditions of section II—III. By it contacts 23—24 are moved to the right, as earlier stated.

In appearing at the exit location III, each intervening "off" period pulse of negative polarity "feed back" energy flows left-to-right current through relay KR over a path that extends from rail 2 through conductor 11, the winding of relay KR, conductor 28, back contact 5 of master coder CR and conductors 9—10 back to the rail 1. This current flow takes place during the master code "off" periods and can occur only when section II—III is unoccupied. By it contacts 23—24 are moved to the left, as earlier stated.

By these contacts 23—24 of detector relay KR the earlier named approach relay AR is controlled in such manner as to receive pick-up energy when and only when the detector relay is following code. This approach relay AR is of the direct current type and contact 26 thereof is sufficiently slow in releasing to assure continuous pick-up during code following operation of relay KR.

Any suitable form of approach relay energizing circuit may, of course, be used. In the arrangement of Fig. 1, the approach relay pick-up current originates in course "plus"—"minus," and is transmitted to the relay through pole changing contact 23 of device KR, an interposed transformer AT and rectifying contact 24 of device KR. In the generally equivalent arrangement which Fig. 4 shows, the transformer AT is dispensed with and pick-up current is transmitted to relay AR directly over contact 23 of device KR.

As arranged in Fig. 1, relay AR can receive energizing current only if the detector device contacts 23—24 are recurrently shifting between their right and left positions. Stoppage of those contacts in either position results in a complete deenergization of relay AR and the resultant release of its contact 26.

By such release, any desired form of approach energization control may be performed. As illustratively shown in Fig. 1, contact 26 maintains wayside signal SIII disconnected from its lamp lighting source when picked up and completes a signal energizing connection when and only when released.

The non-line-wire approach control combination which has just been described utilizes the "coded feed back" operating principles of the earlier named Nicholson Patent No. 2,021,944 and its mode of operation will have become more or less apparent from the foregoing description of the entrance end and of the exit end apparatus which the Fig. 1 track circuits utilize.

Under both vacant and occupied conditions of section II—III, the continuously operating coder relay CR recurrently connects the section rails with the exit end source TB and thereby produces a "master code" of the character shown in Fig. 2. Under vacant conditions of the section, the energy pulses of this master code are transmitted to the section entrance II where they operate the track relay TR in conventional code following manner.

Through the medium of impulse relay IR, such operation causes the section rails to be momentarily connected with the entrance source KB during each "off" period of the received master code. These connections produce "feed back" energy pulses which are of the character represented by the lower portion of Fig. 2 and which have a polarity opposite to that of the master code energy pulses.

In being received at the exit location III, these feed back energy pulses aid the master code energy pulses in operating the detector relay KR in the code following manner earlier described. As a result of such operation, approach relay AR is caused to hold contact 26 continuously picked up and thereby to maintain wayside signal SIII normally deenergized.

In the event that a train comes into section II—III, the usual shunting action of its wheels and axles cuts off transmission of "master code" energy to the entrance end track relay TR and also discontinues transmission of "feed back" energy to the exit end detector relay KR. Now receiving only the master code pulses, relay KR holds contacts 23—24 continuously in their right or reverse position.

As a result, transformer AT now discontinues all transmission of pick-up energy to relay AR and causes that relay to release contact 26. That release, of course, connects wayside signal SIII with its lighting source and thereby causes that

signal to display the particular indication which is selected by decoding equipment H—D.

This release of the approach relay AR continues until the train moves out of section II—III. When that happens, master code energy is again transmitted to entrance end track relay TR, the section rails are once more supplied with feed back pulses and those pulses again aid the master code energy in operating the exit end detector relay KR in code following manner. By that operation, the approach relay AR is picked up and wayside signal SIII is thereby restored to its normally inactive condition.

Direct current track circuits of the "coded feed back" type frequently have to safeguard their "feed back" energized relays against false operation due to inductive "kick back" energy which may be generated in the track rails when those rails are shunted. In the track circuit of Fig. 1, such so-generated "kick back" energy appears in rails 1—2 at the end of each "on" period pulse of unidirectional current with which master source TB supplies those rails over front contact 5 of coding device CR.

Direct current track circuits employing "detector" relays of the type shown at KR in Fig. 1 can experience serious operating difficulties due to such "kick back" energy and one early proposal to overcome such difficulties forms the subject of assignee's earlier mentioned Patent No. 2,286,002 to Nicholson.

As the specification of that Nicholson patent sets forth in considerable detail, "kick back" energy of the type here considered results from the inductance of the track circuit plus the conductance of the rail-to-rail ballast and its effect is to continue for a short interval after each disconnection of source TB from the section rails the flow of current in those rails in the same direction as source TB had established.

When, therefore, the rails of Fig. 1's section II—III are shunted by a train each "on" period pulse of master code current that is impressed upon those rails by source TB may be followed by a "kick back" energy pulse, which though relatively short, still is long enough to overlap the early portion of the succeeding "off" code period (see Fig. 2). "Off" period current due to these overlapping pulses thus may flow from rail 2, over conductor 11, through the winding of relay KR in the direction of from left to right, conductor 28, device CR's back contact 5 and conductors 9—10 back to rail 1.

If of sufficient magnitude each pulse of such "off" period "kick back" current will shift contacts 23—24 of relay KR out of their right or master-energy established position into their left position. This response is the same as that which "feed back" energy received from the section entrance produces and under occupied section conditions it may cause relay KR falsely to follow code.

Assume, for example, that a train has passed location II and is shunting rails 1—2 some distance from location III. Under this condition, detector relay KR should hold contacts 23—24 continuously to the right and thereby indicate that section II—III has become occupied. In the absence of counteracting means the just described master "kick back" energy may prevent such holding and cause relay KR to continue to follow code even though no feed back energy is being transmitted thereto.

In order to guard against such false operation of detector relay KR the exit end apparatus of

Fig. 1 makes use of a reactor 27. This reactor was previously named in tracing the circuit over which relay KR receives "on" period current pulses from master source TB. In addition to forming a part of that circuit, reactor 27 keeps relay KR's winding connected with rails 1—2 during the early portion of each master code "off" period when coding contact 5 shifts from its front to its back position.

Such connection enables advantage to be taken of the inductive characteristics of relay KR's winding plus those of the reactor 27. Such characteristics result in the generation of a local "kick back" voltage at the end of each passage of unidirectional current from source TB through the reactor and relay winding. That generation is, of course, produced by the collapse of magnetic flux which accompanies each disconnection of the named elements from source TB.

Upon each of those disconnections: (1) the energy stored in the circuit of the section rails 1—2 tends to flow through the winding of relay KR from left to right; and (2) the energy of self-inductance in relay KR's winding plus that in reactor 27 tends to continue the flow of current through the winding relay KR in the opposite or right-to-left direction.

These currents directly oppose each other and by choosing the magnitude of the winding's plus reactor's "kick back" current to slightly exceed that generated in the rails, the contacts 23—24 of relay KR are effectively held to the right following each disconnection of master code source TB from the shunted rails.

In practice reactor 27 may take the form of an adjustable element which is set at such a value as to produce the relation just expressed. Should relay KR's winding itself be capable of producing all of the counter inductive effect that is needed, then the reactor 27 may be replaced by a resistor (not shown) or other impedance. When employed as is device KR at location III of Fig. 1 most code following relays of commercial design are, however, found to require some counter inductive supplement and for this reason use of the represented reactor for element 27 ordinarily will be preferred.

When organized as at exit location III of Fig. 1 this reactor element 27 exerts its "kick back" neutralizing effect during the initial or early portion only of each "off" code period. This is because each "off" period closure of coding device CR's back contact 5 by-passes element 27 and thus leaves only the winding of relay KR to oppose the reactive effect of the rail circuit.

In practice, however, this by-passing of reactor 27 by back contact 5 is found to detract but little or nothing from that reactor's effectiveness as a neutralizer of rail "kick back" current. Such current rises to its highest level immediately after coding contact 5 leaves its front position at the master code pulse end and it is found to attain that level before contact 5 reaches its back position. All during this interval reactor 27 is exerting its full neutralizing effect. By the time, in consequence, that contact 5 reaches its back position that rail "kick back" current either is completely overcome or is so greatly diminished that the reactive effect of relay KR's winding alone readily holds it in check.

In the improved entrance end organization which I have shown at location II in Fig. 1, use is made of a comparable reactor 29. This reactor keeps relay TR's winding connected with the section rails during the master code "off".

periods when relay IR's contact 6 is picked up. Its function is to safeguard track relay TR against false response due to inductive "kick back" energy that may be present in the track rails immediately following the feed back pulse ends.

As previously explained relative to Fig. 1's exit end reactor 27, such "kick back" energy results from the inductance of the track circuit plus the conductance of the rail-to-rail ballast; it is likely to be present in the rails of a shunted track section at the end of each direct current energy pulse that is impressed thereon; and when so generated its effect is to continue for a short time after each disconnection of the D.-C. source from the rails the flow of rail current in the same direction as was established by that source.

If such feed back "kick back" energy persists after device IR's contact 6 has reconnected track relay TR to the section rails, it will, therefore, flow current through relays TR in such direction as falsely to pick the relay up. Under certain operating conditions of track section II-III, such false pick-up is highly objectionable and the purpose of added reactor 29 is to make it impossible.

In achieving the stated pick-up prevention by feed back "kick back" energy, advantage is taken of the inductive characteristics of relay TR's windings plus those of reactor 27 and their effect in generating a local "kick back" voltage at the end of each application of direct current to the relay winding. The stated effect is produced by the collapse of magnetic flux which accompanies each disconnection of the winding and reactor from feed back source KB. Reactor 29 establishes for relay TR's winding a connection through which each pulse of trackway energy from that source KB flows current through the winding of relay TR in the direction of from right to left.

As earlier explained, such current flow is ineffective for picking up relay TR and thus it does not interfere with the desired code following response of that relay to the master code energy pulses which are applied thereto. It does, however, render the relay immune to false pick-up by feed back "kick back" energy which may be applied thereto over device IR's back contact 6 following disconnection of source KB from the section rails.

Upon each of these disconnections: (1) the section rails 1-2 tend to flow through the winding of relay TR a feed back "kick back" current in the direction of from left to right; and (2) the energy of self-inductance in relay TR's winding tends to continue the flow therethrough of current in the opposite or right-to-left direction.

These currents directly oppose each other and by choosing the magnitude of the winding's plus reactor's kick back current to slightly exceed that generated in the rails, relay TR is effectively held released following each disconnection from the rails of feed back source KB.

In practice reactor 29 may take the form of an adjustable element which is set at such a value as to produce the relation just expressed. Should relay TR's winding itself be capable of producing all of the counter inductive effect that is needed, then the reactor 29 may be replaced by a resistor (not shown) or other impedance. As, however, most code following relays of commercial design are found to require some counter inductive supplement, use of the represented

reactor for element 29 will ordinarily be preferred.

When organized as at entrance location II of Fig. 1 this reactor element 29 exerts its "kick back" neutralizing effect only from the instant that impulse relay IR's contact 6 leaves its front position at the "feed back" pulse end until the slightly later instant that contact 6 reaches its back position. This is because each back closure of contact 6 by-passes element 29 and thus leaves only the winding of relay TR to oppose the reactive effect of the rail circuit.

In practice, however, this by-passing of reactor 29 by back contact 6 is found to detract but little or nothing from that reactor's effectiveness as a neutralizer of rail "kick back" current. Such current rises to its highest level immediately after the impulse of relay contact 6 leaves its front position and it is found to attain that level before contact 6 reaches its back position. All during this interval reactor 29 is exerting its full neutralizing effect. By the time, in consequence, that contact 6 reaches its back position that rail "kick back" current either is completely overcome or is so greatly diminished that the reactive effect of relay TR's winding alone readily holds it in check.

In addition to assuring that the master track relay TR and the feed back detector relay KR will not falsely respond to inductive "kick back" energy received from the section rails, the complete coded feed back track circuit combination of Fig. 1 also protects the two relays just named from unsafe response: (1) in the event that contact 5 of master coder CR fails to interrupt the rail supply path from master source TB before establishing the rail connecting path for detector relay KR or fails to interrupt the detector relay path before establishing the master source path; and (2) in the event that contact 6 of impulse relay IR fails to interrupt the rail connecting path for master track relay TR before establishing the rail supply path for feed back source KB or fails to interrupt the feed back supply path before establishing the track relay circuit.

In both instances, this "bridging contact" protection is a direct by-product of the opposing polarity relation between the pulses of "master code" energy from exit end source TB and the pulses of "feed back" energy from entrance end source KB. This relation has already been described in detail and is clearly indicated by the diagram of Fig. 2.

Looking first at location III's combination of exit end devices CR-TB-KR, assume that contact 5 of relay CR is incorrectly adjusted or builds up so that it engages its front and back points at the same time. Such a condition causes master source TB to be continuously connected both with the rails of section II-III and with the winding of detector relay KR. That relay, quite obviously, now holds its contacts 23-24 continuously to the right and at the entrance location II track relay TR is held continuously picked up. Both of these stoppages of code following operation simulate the effects which a shunting of the section rails 1-2 produces and neither is in any way unsafe.

Looking next at location II's combination of entrance end devices IR-KB-TR, assume that contact 6 of relay IR is incorrectly adjusted or builds up so that it engages its front and back points at the same time. In that event, feed back source KB is continuously connected both

with the section rails 1—2 and with the winding of the track relay TR. As a result of that connection, relay TR is held continuously released. As in the preceding instance of contact bridging, this effect is on the safe side.

A further advantage of the Fig. 1 track circuit organization resides in its inherent tendency to keep "rail storage" potentials at a level far below that required to falsely operate either of the rail connected relays TR and KR. As is well known, each pulse of applied trackway energy, particularly in a direct current system of the type here shown, causes to be built up between the section rails a "storage" potential which persists for a short time after the energy ceases to be applied.

When, as in prior track circuit combinations of the type which the earlier named Nicholson Patent No. 2,286,002 typifies, the "master" and the "feed back" energy pulses have a coinciding polarity relation, the build up effect tends to be cumulative and the level of storage potential may then build up and substantially delay release of the track relay contacts on termination of each impulse of master code.

In my improved organization, however, the opposing polarity relation (see Fig. 2) of the master and feed back pulses directly counteracts this tendency of storage potential build-up. Each pulse of positive polarity master code energy is followed by a negative polarity pulse of feed back energy which, in turn, is followed by a positive pulse of feed back energy, and so on. In consequence, storage potential of neither polarity has a chance to build up to an objectionable level.

Alternative connections of Figs. 3-4

As has already been seen, the improved "coded feed back" control circuit combination of my invention is characterized by: (1) use of "master code" and "feed back" energy pulses which have an opposing polarity relation in the control circuit conductors; (2) connection of the feed back detector relay KR to those conductors in multiple with the master energy source TB and connection of the master code following relay TR to those conductors in multiple with the feed back energy source KB; and (3) serial inclusion in those connections of reactors 27 and 29 by which conductor "kick back" energy is prevented from falsely operating relays KR and TR.

As might be expected, the earlier described Fig. 1 illustrates only one of a number of possible apparatus connections by which the just stated features may be provided. In Figs. 3 and 4, other possible organizations of the entrance and of the exit and elements are respectively represented.

In the modified entrance end organization of Fig. 3, the "kick back" neutralizing reactor 29 is included in rail conductor 14 (instead of in conductor 17 as in Fig. 1); the feed back source KB is interposed between rail conductor 17 and impulse relay IR's front contact 6 (instead of joining with conductor 20 as in Fig. 1); and conductor 15 connects relay IR's back contact 6 with the left terminal of master track relay TR (instead of with relay TR's right terminal as in Fig. 1).

Despite these modifications, the entrance end apparatus of Fig. 3 has operating characteristics which duplicate those of Fig. 1. Each positive or "given" polarity pulse of master code energy which reaches location II picks up track relay TR over a circuit extending from track rail 1 through conductors 14 and 20, back contact 6 of device IR, conductor 15, the winding of relay TR and conductor 17 back to rail 2.

As in Fig. 1, the energy impressed by transformer RT upon impulse relay IR due to this pick-up by relay TR fails to move contact 6 from its released position. In consequence, that contact keeps the feed back source KB disconnected from the section rails during the full "on" period of the received master code.

As in Fig. 1 also, the release of track relay TR which accompanies each master code "off" period causes transformer RT to supply impulse relay IR with a short pulse of pick-up energy. Responding to this pulse, relay IR picks up contact 6 and thereby: (1) inserts reactor 29 in the track relay circuit; and (2) connects feed back source KB with the section rails.

Because of this connection, the rails now are supplied with an "off" period pulse of feed back energy over a path extending from the positive terminal of source KB through current limiting impedance 19, conductor 17, the track rails 2 and 1, conductors 14 and 20 and front contact 6 of device IR back to the negative terminal of source KB.

As in Fig. 1, this so-supplied feed back energy pulse has a negative or "opposite" polarity and continues for the relatively short duration represented in Fig. 2. Within the master code "off" period which initiated the pulse, relay IR releases and terminates the pulse by disconnecting source KB from the section rails.

Following this disconnection, relay IR's contact 6 sets up a shunt path around reactor 29 and thus conditions track relay TR for reception of and response to the succeeding "on" period pulse of given polarity master code energy. When that pulse is received there is started a sequence of actions which duplicate those just described.

As in Fig. 1, the reactor 29 of Fig. 3 renders track relay TR immune to false pick-ups by rail "kick back" energy that follows each disconnection of feed back source KB from the track circuit. Inasmuch as the Fig. 3 organization confers this immunity in a manner fully equivalent to that earlier explained for the Fig. 1 organization, no further description of this action is here believed necessary.

Referring now to Fig. 4, the exit end apparatus organization there shown will be seen to bear to the location III apparatus of Fig. 1 a relation comparable to that just explained between the entrance end organization of Fig. 3 and the location II apparatus of Fig. 1.

In Fig. 4, detector relay KR's reactor 27 is included in rail conductor 11 (instead of in conductor 10 as in Fig. 1); the master energy source TB is interposed between rail conductor 10 and coder relay CR's front contact 5 (instead of being joined with conductor 12 as in Fig. 1); conductor 28 joins relay CR's back contact 5 with the left terminal of detector relay KR's winding (instead of with the right terminal as in Fig. 1); and the detector relay controlled approach relay AR receives pick-up current directly over relay KR's left or reverse contact 23 (instead of through an interposed transformer AT as in Fig. 1).

Despite the several detail changes just named, the exit end apparatus of Fig. 4 has operating characteristics which are equivalent to those earlier explained for the corresponding elements of Fig. 1.

Each pick-up of coder relay CR's contact 5 causes source TB to supply the section rails with an "on" period pulse of normal polarity master code energy. The pulse supply path extends from the positive terminal of source TB through

current limiting impedance 8, conductor 10, track rails 1 and 2, conductors 11-12 and front contact 5 of device CR back to the negative terminal of source TB.

During this master code "on" period, source TB also flows current through the winding of relay KR over a path extending from the source's positive terminal through impedance 8, the winding of relay KR, reactor 21, conductor 12, and device CR's front contact 5 back to the source's negative terminal. The direction of this current flow is from right to left and it causes relay KR to operate contact 23 to the right or "reverse" position illustrated.

In moving to the released position at the master code "on" period end, device CR's contact 5 disconnects source TB both from the section rails and from the winding of detector relay KR. Such disconnection establishes a master code "off" period and connects the winding of relay KR directly with the section rails 1-2. Contact 23 of the now deenergized relay KR continues to occupy the right position shown, and is shifted away from this position only when negative or "opposite" polarity feed back energy is received by relay KR.

Under vacant conditions of the track section behind location III, such reception occurs (see Fig. 2) early in each so-defined master code "off" period. By the then received pulse of opposite polarity feed back energy, relay KR is energized over a path extending from track rail 2 through conductors 11-12, device CR's back contact 5, conductor 28, the winding of relay KR and conductor 10 back to track rail 1.

The flow of feed back current through relay KR is from left to right and by that flow contact 23 is operated to the left or "normal" position. As in Fig. 1, this contact positioning continues until relay KR receives another "given" polarity pulse of master code energy. Contact 23 stays to the left, therefore, even after the "off" period pulse of feed back energy has been terminated.

In picking up at the "off" period end, device CR's contact 5 reinserts reactor 21 into relay KR's energizing circuit and reconnects master source TB both with the section rails and with relay KR's winding. Such reconnection establishes another master code "on" period and starts a sequence of operations which duplicates that just explained. By the first of those operations relay KR shifts contact 23 back to the right or reverse position illustrated.

Under vacant section conditions, therefore, detector relay KR at Fig. 4's location III is caused to position contact 23 to the right during each "on" period pulse of master code energy that is supplied to the section rails and to position contact 23 to the left during each "off" period pulse of feed back energy that is received from those rails. As in Fig. 1, such shifting is effected by the opposing polarity relation between the master and feed back energy.

During such code following operation by relay KR's contact 23, Fig. 4's approach relay AR is supplied with code step pulses of pick-up energy over a path extending from the positive terminal of a local control source through the winding of relay AR and back to the negative terminal of the control source.

As in Fig. 1, contact 26 of relay AR is made sufficiently slow releasing to bridge the master code "on" periods and by the recurring pulses of approach relay pick-up energy just named,

contact 26 is accordingly held continuously picked up. Such a positioning of the contact indicates that the track section to the rear of location III is vacant and that "off" period pulses of negative polarity feed back energy are being received from entrance apparatus which may duplicate that shown at location II in either of Figs. 1 or 3.

When a train comes into the section to the rear of Fig. 4's location III, the shunting action of its wheels and axles cuts off the just named feed back energy transmission and thereby deprives detector relay KR of all negative polarity energization. As in Fig. 1, the relay continues to receive positive pulses of master code energy and accordingly holds contact 23 continuously to the right. Because of this holding, the approach relay AR is now deprived of all pick-up energy and that relay's contact 26 accordingly releases. By that release, an occupied condition of the track section is indicated.

By Fig. 4's reactor 21 the detector relay KR is rendered immune to false operation by rail "kick back" energy that may result from each of coding contact 5's interruptions in the connection of the master energy source TB with the track circuit. Inasmuch as the actions incident to this immunity are the same as those previously explained for the exit end organization of Fig. 1, no further description thereof is here deemed necessary.

In addition to this "kick back" energy immunity the exit end apparatus organization of Fig. 4 offers protection against "foreign" rail current which is comparable to that offered by the corresponding organization of Fig. 1. If the foreign current makes rail 1 continuously positive with respect to rail 2, the effect thereof on detector relay KR is to urge contact 23 to the right. Under vacant section conditions, this effect may prevent the negative polarity feed back pulses from operating contact 23 to the left and in that event approach relay AR will release contact 26 in the same manner as were the section occupied. Under occupied conditions of the section, the negative polarity foreign rail energy merely aids master source TB in holding relay KR's contact 23 to the right and therefore does not disturb the normally released positioning of approach relay AR's contact 26.

The just stated "safe" response to "foreign" rail energy of negative polarity is effected not only by the exit end apparatus of Fig. 4 but also by the exit end apparatus of Fig. 1. There a continuous positioning of detector relay contacts 23-24 either to the right or to the left effects the continuous release of approach relay AR's contact 26.

With either of those arrangements, however, some false operation might be experienced if the "foreign" rail energy continuously makes rail 2 positive with respect to rail 1. In that event, the detector relay KR of both Figs. 1 and 4 might conceivably follow code at a time when the extreme entrance end II of the section was shunted by a train. As the train approached exit location III, however, such false operation would soon cease—due to the reduction in foreign rail potential which would necessarily accompany the advancing rail shunt.

Mention has already been made of an earlier developed "coded feed back" track circuit organization which is disclosed and claimed by assignee's recently issued Patent No. 2,286,002 to Nicholson. In that Nicholson organization: (1)

the exit end master source TB utilizes a series connection with the detector relay KR for supplying "on" period pulses of master code energy to the section rails; (2) the entrance end feed back source IB (corresponding to element KB hereof) utilizes a similar series connection with the track relay TR for supplying "off" period pulses of feed back energy to the section rails; and (3) the polarity relation in each of these connections is such that current from the connection-included source flows through the winding of the connection-included relay in a direction which is opposite to the flow of winding current that is produced by relay operating energy received from the opposite end of the section.

In the case of Nicholson's "polar biased" track relay TR at the section entrance, the just stated relation is necessary to prevent that track relay from being falsely picked up by the "off" period pulses of rail current that the feed back source flows through that relay's winding. Similarly, in the case of Nicholson's "polar stick" detector relay KR at the section exit, the named polarity relation is imperative in order that the "on" period pulses of master rail current which exit end source TB flows through that detector relay's winding will operate the relay's polar contacts to a position opposing that to which they are operated by the "off" period pulses of feed back energy that are received from the section entrance.

Because of the requirements just explained, the Nicholson combination must utilize master and feed back energy pulses which have a coinciding polarity relation. In certain instances, as a previous portion of this specification has already indicated, such polarity coincidence is not entirely desirable in that it permits "rail storage" potential to cumulatively build up instead of being held in check as in the staggered polarity organization of my present invention.

As compared with the Nicholson organization, therefore, the improved "coded feed back" track circuit combination herein disclosed offers the important advantage of utilizing a staggered polarity relation between the master and feed back energy pulses and of thereby minimizing the "storage" potential that tends to build up between the track rails as a result of coded direct current energy application thereto.

Cab signal only organization of Figs. 5-6

A further difficulty with the Nicholson organization is encountered when attempts are made to provide for the control of train-carried cab signals. In accordance with present preferred signaling practice, such provision requires that alternating current energy be superimposed upon the direct current "master" pulses which are applied to the section exit and which recur at a rate that is distinctive of traffic conditions in advance of the application point.

In the earlier discussed Nicholson organization these direct current master energy pulses are impressed upon the section rails over a series connection with the detector relay KR's operating winding and any alternating current cab signal control energy that is superimposed upon those master pulses must, therefore, also flow through the detector relay winding. When alternating current cab signal control energy is supplied to the section rails through the winding of the feed back detector relay, this relay must be of a type which will not respond to this energy. This pre-

vents the use of a sensitive relay at this point and therefore limits the length of track section over which the track circuit may be operated.

The improved "coded feed back" track circuit organization of my invention overcomes this shortcoming and provides for the supply of alternating current energy to the section rails over a circuit which does not include the feed back detector relay in series therewith. One preferred manner in which such facilities may be combined with my earlier explained basic form of "coded feed back" track circuit organization is shown by the diagram of Fig. 5.

In that diagram there is reproduced: (1) at entrance location II the entrance end apparatus of Fig. 1 modified to utilize a decoding transformer DT in place of the impulse relay transformer RT and to dispense with the wayside signal SII; and (2) at the exit location III the exit end apparatus of Fig. 1 modified to show the driving facilities for master coder relay CR, to dispense with the wayside signal SIII, and to include in the rail supply circuit of direct current master source TB a track transformer TT through which energy from an alternating current source B-C of 60 cycle per second or other commercial carrier wave frequency is at proper times supplied to the section rails.

The track circuit organization of Fig. 5 is intended for use in a "frequency code" block signaling system of the "cab signal only" type wherein all signal indications along the wayside are dispensed with and traffic movements are governed solely through the medium of train-carried apparatus of the conventional character represented in Fig. 6.

By that figure there is shown train-carried cab signal circuits which are of conventional "frequency selective" character and which embody principles and apparatus that are more completely described by Paul N. Bossart Patent No. 1,773,472 dated August 19, 1930.

In these Fig. 6 circuits, use is made of the usual pick-up windings 32-33 mounted on the locomotive front; an amplifier 35 that strengthens the energy which these windings inductively receive from the track rails 1-2; a code following master relay MR which is energized through a transformer 36 by a measure of the output of this amplifier and which responds to each pulse of received trackway energy having the alternating current character that is supplied from source terminals B-C of Fig. 5; a decoding transformer DT which is supplied with code step pulses of exciting current over a pole changing contact 17a of the master relay; frequency selective circuits DU into which the decoding transformer feeds its output energy; decoding relays HR and DR which receive pick-up current from these frequency selective circuits; and a cab signal CS having a plurality of indicating units which are selectively energized under the control of the decoding relays.

The elements just named cooperate in such a way that: (1) when the master relay MR follows alternating trackway code of the 180 pulse per minute variety both of the decoding relays HR and DR pick up and light (over front contacts 38-39) the green or "clear" indication lamp G of the cab signal CS; (2) when the master relay follows alternating current trackway code of the 75 pulse per minute variety only the first decoding relay HR picks up and front contact 38 plus back contact 39 then complete the

lighting circuit for the yellow or "approach" indication lamp Y of the signal; and (3) when the master relay ceases to follow code and holds contact 17a continuously in one position both of the decoding relays release and light (over back contacts 38-39) the red or "stop" indication lamp R of the cab signal.

The trackway organization of Fig. 5 supplies the rails of section II-III with the alternating current energy which is required to operate the cab signal apparatus of Fig. 6 and it does this without in any way interfering with the desired or safe operation of the exit end detector relay KR.

While the track transformer TT of this Fig. 5 organization might at all times be connected with the alternating current source terminals B-C, it is preferable that this transformer energizing connection be completed only when a train comes into the section to the rear of the transformer location. For so approach energizing transformer TT, use is made of a contact 41 carried by the approach relay AR. Under vacant conditions of section II-III this contact is picked up and it then by-passes the primary of transformer TT and thereby reduces the impedance offered by that transformer's secondary to the flow therethrough of direct current from master code source TB.

Under occupied conditions of section II-III, relay AR's contact 41 is released and alternating current from source B-C then continuously excites transformer TT over a circuit extending from terminal B through back contact 41, conductor 42, the primary of transformer TT and conductor 43 back to terminal C. As a result of this excitation, transformer TT superimposes upon each of the direct current "master" energy pulses from source TB the component of alternating current energy earlier described as being suitable for train-carried cab signal control.

As long as any part of the train continues in section II-III, each pick-up of master coder relay CR's contact 5 causes the section rails to receive this alternating current energy from transformer TT. In the illustrative arrangement of Fig. 5, the supply path extends from the lower terminal of TT's secondary through conductor 44, track battery TB, impedance 8, front contact 5 of device CR, conductors 9-10, track rails 1-2 and conductors 11-12 back to the upper terminal of TB's secondary.

Upon passage of the train out of the section II-III, master code energy from the direct current source TB once more reaches and operates entrance end track relay TR. That operation causes impulse relay IR to connect feed back source KB with the section rails during the master code "off" periods and as a result of those connections exit end detector relay KR once more follows code and picks up approach relay AR. By that pick-up contact 41 disconnects transformer TT from source B-C and thereby removes all alternating current energy from the section rails.

As in the exit end organization of Figs. 1 and 4, the detector relay KR at Fig. 5's exit location III receives current from direct current source TR during each "on" period of pulse of master code energy which that source supplies to the rails. This reception is by way of a "kick back" neutralizing reactor 27 and in each of Figs. 1, 4-5 the "on" period current so impressed upon relay KR serves to return that re-

lay's contacts to the right in order that each received pulse of feed back current will shift them to the left.

By Fig. 5's reactor 27 the detector relay KR 5 is rendered immune to false operation by rail "kick back" energy that may result from each of coding contact 5's interruptions in the connection of the master energy source TB with the section rails. Inasmuch as the actions incident to 10 this immunity are the same as those previously explained for the exit end organizations of Figs. 1 and 4, no further description thereof is here deemed necessary.

In order that Fig. 5's coded pulses of alternating current energy will not objectionably affect the detector relay KR, the "kick back" neutralizing reactor 27 in that relay's energizing circuit may be supplemented by an inductance 30 which while freely passing unidirectional current from 20 source TB excludes to a large extent the flow of alternating current from source B-C. Use of this added inductance 30 is, however, optional since it is possible to design the direct current detector relay KR in such manner that its contact 23 will not follow the A-C. frequency reversing polarity current which the relay receives through reactor 27 from the cab signal control source B-C.

For selecting in accordance with advance traffic conditions the rate at which master coder relay CR operates, the complete track circuit organization of Fig. 5 utilizes the usual code detecting relay H. As shown at exit location III, this relay has a contact 46 which when picked up 30 connects coder device CR's driving circuit with contact 180 of a high speed code transmitter CT180 and which when released connects the same driving circuit with contact 75 of a low speed code transmitter CT75. Under the condition first stated, relay CR produces a "master code" made up of 180 energy pulses per minute and under the condition last stated device CR produces a "master code" made up of 75 energy pulses per minute.

This exit end relay H is associated with the section in advance of location III and it is controlled in the manner shown at section II-III's entrance location II. As long as track relay TR 50 follows code of either the 180 or the 75 pulse per minute rate, decoding transformer DT1 supplies (over a rectifying contact 18) relay H with winding current which holds contact 46 continuously picked up. Upon failure of track relay 55 TR to follow code, however, this winding current supply is discontinued and contact 46 then releases.

From the foregoing description of the coded track circuit apparatus of Fig. 5 and of the train-carried cab signal equipment of Fig. 6, it will be apparent that a three indication system of automatic block cab signal control may be provided by equipping each of a plurality of consecutive track sections with this Fig. 5 apparatus and arranging that the entrance end relay H of each section determine (by means of contact 46 as shown at location III) the rate of pulse recurrence of the direct current plus alternating current (when needed) "master code" energy that is supplied to the exit end of the rear adjoining section.

Trains equipped with the cab signal apparatus of Fig. 6 thus set up in customary three indication automatic block manner their own following

protection in passing through such a signaled stretch of track.

Referring to Fig. 7, I have there shown one alternative organization for the code producing and selecting facilities of Fig. 5's location III. In it Fig. 5's code repeater relay CR is dispensed with and the circuits over which sources TB and TT supply energy to the section rails are carried directly over contacts 180 and 75 of code transmitters CT180 and CT75.

As in Fig. 5, selection between those code transmitter contacts is effected by contact 46 of relay H. When that relay is picked up (as shown) transmitter contact 180 performs the functions of Fig. 5's repeater contact 5 and when relay H is released transmitter contact 75 performs the functions of Fig. 5's repeater contact 5.

In either instance, each pick-up of the selected transmitter contact connects sources TB-TT in energy applying relation with the section rails 1-2 and each released positioning of the selected transmitted contact transfers the rail connection directly to the winding of detector relay KR. In consequence, the modified exit end apparatus of Fig. 7 operates in a manner which is the full equivalent of that earlier explained for the exit end apparatus of Fig. 5.

Wayside and cab signal organization of Figs. 8-9

By extending the trackway apparatus organization of Figs. 5 and 7, the cab signal control functions thereof may be supplemented by indications displayed by wayside signals S. Fig. 8 shows one preferred form which such wayside supplements may take.

The "coded feed back" track circuit diagram of that figure: (1) reproduces at entrance location II the entrance end apparatus of Fig. 5 and additionally shows a wayside signal SII plus a code distinguishing relay D plus signal control contacts 38-39 carried by relays H-D; and (2) reproduces at exit location III Fig. 5's exit end apparatus modified in accordance with Fig. 7, and additionally shows a wayside signal SIII plus indication selecting apparatus H-D therefor plus an approach lighting contact 26 carried by relay AR.

This exit location III apparatus of Fig. 8 supplies the rails of section II-III: (1) with 180 pulse per minute "master code" energy when the section in advance of location III is vacant; and (2) with 75 pulse per minute "master code" energy when that advance section is occupied.

At Fig. 8's entrance location II: (1) reception of the 180 master code energy causes track relay TR to produce pick-up on the part of both of the decoding relays H and D and thereby places wayside signal SII at "clear"; (2) reception of the 75 master code energy produces pick-up on the part of decoding relay H only and thereby causes signal SII to show "approach"; and (3) absence of received master code energy allows decoding relays H and D both to release and thereby places signal SII at "stop." The just described response of relay D to 180 code energy only results from an inclusion of a frequency selective unit 180DU in the circuit over which the relay receives pick-up energy from decoding transformer DT2.

The mode of operation of Fig. 8's complete track circuit combination will have become apparent from the earlier given descriptions of that combination's several organizations of individual apparatus elements.

Trains equipped with cab signaling apparatus

of the type shown in Fig. 6 receive on board their leading vehicles automatic block indications due to transformer TT's supply of alternating current energy pulses during all occupied conditions of section II-III; moreover, trains passing through the signaled stretch further receive from the wayside signals S automatic block indications of conventional three indication character. Both the wayside signals S and the cab signal supply transformers TT are approach energized—through the medium of my improved "feed back" apparatus organization.

Referring to Fig. 9, the improvements of my invention are there shown as being applied to an organization of exit end apparatus which is alternative to that shown at location III in Fig. 8. Here the feed back detector relay takes the form of a double-winding device KRX of the "polar biased" type which is organized in a manner more completely described by assignee's Patent No. 2,275,838 to Herman G. Blosser and which picks up only in response to a flow through winding 52 of current in the direction of from left to right.

By this Fig. 9 organization use is made of a master coder CR having two contacts 5 and 50 which operate in synchronous relation with respect to each other. Controlling the driving circuit of this relay CR are code transmitter facilities of the type shown at location III in Fig. 5.

When contacts 5 and 50 are picked up, master energy source TB supplies the section rails (not shown in Fig. 9) with a pulse of master code energy. The supply circuit extends from the positive terminal of source TB through conductor 48, front contacts 5 and 50 in parallel, conductors 49 and 10, the section rails 1 and 2 (see Fig. 8), conductor 11, current limiting impedance 8, the secondary of transformer TT and conductor 44 back to the negative terminal of source TB.

When device CR's contacts are released the connection just traced is interrupted and the pick-up winding 52 of detector relay KRX then is bridged across the section rails. This bridging is over a circuit that extends from rail 2 (see Fig. 8) through conductor 11, relay KRX's winding 52, conductor 54, back contact 5 of device CR, and conductors 53, 49 and 10 back to rail 1 (again see Fig. 8). Over that circuit each pulse of feed back energy that is transmitted to location III (from entrance end apparatus of the character shown at location II in Fig. 8) picks up this detector relay KRX at the beginning of the master code "off" period during which the pulse is received.

A further effect of the release of coder relay CR's contact 50 is to complete an energizing circuit for a stick winding 56 of detector relay KRX and for the pick-up winding of the approach relay AR. In addition to back contact 50 of device CR, this circuit includes a front contact 51 of detector relay KRX and it is organized in a manner disclosed and claimed by assignee's Patent No. 2,272,789 which issued to Herman G. Blosser on February 10, 1942.

In the illustrative form shown, this circuit derives its energy from master code source TB and when completed it extends from the positive terminal of that source through conductor 48, device CR's back contact 50, conductor 58, the winding of approach relay AR, front contact 51 of relay KRX, conductor 59, the stick winding 56 of relay KRX and conductor 60 back to the negative terminal of source TB.

Such completion is possible only when relay

KRX is picked up by an "off" period pulse of feed back energy received over the section rails from apparatus of the character shown at location II in Fig. 8. Such reception, in turn, is possible only when the associated track section is unoccupied. Under that condition, relay KRX becomes picked up during each "off" period of the master code which relay CR of Fig. 9 produces.

By the circuit just traced as including back contact 53 of device CR and front contact 57 of relay KRX, the approach relay AR is energized during the master code "off" periods and each pick-up of detector relay KR1 is prolonged for the full duration of the "off" code period during which it occurs.

With this description of prior art structure as a background, the improvements of my invention which I have applied to Fig. 9 will now be considered. These improvements reside in the inclusion between rail conductor 19 and the right terminal of relay KRX's pick-up winding 52 of a reactor 27 by which the detector relay KRX is rendered immune to false pick-up by master "kick back" energy that may be generated in the section rails 1 and 2 (see Fig. 8) upon each disconnection of master source TB therefrom.

As shown in Fig. 9, this reactor 27 is supplemented by an inductance 30 that is occasioned by the alternating current supply transformer TT which comes into action whenever the associated track section (again see Fig. 8) becomes occupied. In situations where the direct current master code energy is not so supplemented by alternating current cab signal energy, this inductance 30 may be dispensed with.

Under occupied conditions of the track section with which Fig. 9 apparatus is associated, transmission of feed back energy to relay KRX's pick-up winding 52 is discontinued and it is desired that relay KR1 then not pick up. The earlier mentioned master "kick back" energy has in certain installations been observed to cause difficulty by virtue of flowing through the winding 52 at the "off" period beginning current which causes relay KRX falsely to operate even though the track section is occupied.

By including reactor 27 in that winding's energizing circuit, I effectively prevent this false operation and do this in a manner closely comparable to that earlier explained for the corresponding reactors 27 and 29 of the earlier presented figures.

The earlier mentioned Blosser Patent No. 2,275,838 omitted all connection between conductors 49 and 54 under picked-up conditions of relay CR's coding contact 5. No energy from master source TB was, therefore, permitted to reach winding 52 during the "on" code periods.

By providing reactor 27 (and inductance 30 when required) I cause current from master source TB to flow through winding 52 during each "on" code period. This current reaches the winding over a path extending from the source's positive terminal through conductor 48, front contact 53 of device CR, conductor 49, inductance 30 (when used), reactor 27, the winding 52, impedance 8, the secondary of transformer TT and conductor 44 back to the negative terminal of source TB.

The direction of this current flow is from right to left through the winding 52 and in a relay of KRX's "polar biased" type, it is ineffective for picking up contact 57. Such pick-up requires a flow of current through winding 52 in the di-

rection of from left to right, as shown by the small arrows. Feed back pulses received from apparatus of the character shown at location II in Fig. 8 produce this pick-up direction flow.

5. The current flowing in the opposite direction from source TB during each master code "on" period causes winding 52 to generate a local inductive "kick back" potential upon interruption of that current at the "on" period end. This local kick back current tends to flow from right to left and it directly opposes the rail kick back energy which reaches the winding 52 at the same "on" period end.

15. As a result of this opposition, master "kick-back" energy generated in the section rails upon each disconnection therefrom of the master source TB is prevented from falsely picking up the detector relay KRX. The character of this master "kick back" energy is identical to that 20. earlier explained and for this reason no further description thereof is deemed necessary.

The track circuit combination of Fig. 10

Referring to Fig. 10, comparable "kick back" 25. neutralizing means are there shown in association with the track circuit portions of a controlled manual block signaling scheme wherein it becomes desirable to relay coded track energy over long distances.

30. In the particular arrangement illustrated, only two track sections VI-VIa and VIa-VII are shown. At location VII, a code transmitter CT1 recurrently picks up and releases contact 5 whenever a controlling switch 64 is closed. At location VI, similarly, a code transmitter CK1 recurrently picks up and releases a contact 6 whenever a controlling switch 67 therefor is closed. In the controlled manual block system earlier mentioned, only one of switches 64 and 67 is closed at any particular time.

35. Under conditions of the represented closure of switch 64 and the opening of switch 67, each pick-up of transmitter CT1's contact 5 causes a source TB1 at location VII to pick up a track relay TR1 at location VIa over a circuit extending from the positive terminal of source TB1 through an impedance 8, CT1's front contact 5, conductors 9 and 10, section rail 1, conductors 14 and 65, back contact 66 of device KR1, conductor 70, 50. the winding of relay TR1, conductors 68 and 17, section rail 2 and conductors 11-12 back to the negative terminal source TB1.

40. Each release of coding contact 5 at location VII interrupts the connection just traced and bridges the section rails 1-2 directly across the winding of a track relay KR2. Included in this bridging connection is back contact 5 and a conductor 28.

45. At the cut location VIa, relay TR1 accordingly picks up and releases its contact 69 in step with the pick-ups and releases of transmitter CT1's contact 5 at location VI. By relay TR1's contact 69 there is recurrently completed a circuit over which a source TB2, at location VIa picks up a track relay TR2 at location VI. This pick-up circuit extends from the positive terminal of source TB2 through conductor 71, front contact 69 of device TR1, conductors 9a and 10a, section rail 1a, conductors 14a and 79, back contact 6 50. of device CK1, conductor 80, the winding of relay TR2, conductor 11a, rail 2a, conductor 11a, and impedance 72 back to the negative terminal of source TB2.

55. Each release of track relay TR1 at location VIa interrupts the circuit just traced and bridges

the section rails 1a—2a directly across the winding of a track relay KR1. Included in this bridging connection is relay TR1's back contact 69 and a conductor 73.

At location VI relay TR2 accordingly picks up and releases its contact 76 in step with the pick-ups and release: (1) of relay TR1's contact 69 at location VIa; and (2) of transmitter CT1's contact 5 at location VII. By this code following action of contact 76 any desired control function peculiar to manual block signaling may be performed.

Under other conditions wherein location VI's switch 67 is closed and location VII's switch 64 is opened, transmitter CK1 recurrently picks up and releases its contact 6 and transmitter CT1 keeps contact 5 continuously released. Each such pick-up of CK1's contact 6 causes a source KB1 at a location VI to pick up track relay KR1 at location VIa over a circuit extending from the positive terminal of KB1 through conductors 78 and 17a, section rail 2a, conductor 11a, the winding of relay KR1, impedance 29, conductor 10a, section rail 1a, conductors 14a and 17, CK1's front contact 6, and impedance 19 back to the negative terminal of source KB1.

Each release of coding contact 6 at location VI interrupts the connection just traced and bridges the section rails 1a—2a directly across the winding of relay TR2. Included in this bridging connection is back contact 6 and the earlier named conductor 80.

At the cut location VIa, relay KR1 accordingly picks up and releases its contact 66 in step with the pick-ups and releases of transmitter CK1's contact 6 at location VI. By relay TR1's contact 66 there is recurrently completed a circuit over which a source KB2 at location VIa picks up track relay KR2 at location VII. This pick-up circuit extends from the positive terminal of source KB2 through impedance 82, conductor 17, section rail 2, conductor 11, the winding of relay KR2, conductor 28, back contact 5 of device CT1, conductors 9—10, section rail 1, conductors 14 and 65, relay KR1's front contact 66 and conductor 83 back to the negative terminal of source KB2.

Each release of track relay KR1 at location VIa interrupts the circuit just traced and bridges the section rails 1—2 directly across the winding of track relay TR1. Included in this bridging connection is relay KR1's back contact 66 and the earlier named conductor 10.

At location VII relay KR2 accordingly picks up and releases its contact 86 in step with the pick-ups and releases: (1) of relay KR1's contact 66 at location VIa; and (2) of transmitter CK1's contact 6 at location VI. By this code following action of contact 86 any control function peculiar to manual block signaling may be performed.

From the diagram of Fig. 10 it will be noted that each of the there represented four track relays TR1, TR2, KR1 and KR2 is of the "polar biased" type the contacts of which pick up only in response to a flow through the relay winding of current in the direction of from left to right, as shown by the arrow. As in the case of device TR of each of Figs. 1, 3, 5 and 8, flow of winding current in the opposite direction merely urges the track relay contacts more firmly into their deenergized or released positions.

From Fig. 10 it will further be noted: (1) that the energy received by each track relay TR1 and TR2 from the parallel-connected sources KB2 and KB1 at the relay location produces this op-

posite direction of current flow and hence is ineffective for picking up that TR relay; and (2) that the energy received by each track relay KR1 and KR2 from the parallel-connected sources TB2 and TB1 at the relay location similarly produces relay current flow in a direction that is ineffective for picking up that KR relay. In a system of the represented controlled manual block type, such a relation is depended upon to assure that the various system functions will be performed in the intended manner.

Because of this relation there is presented the earlier described problem of safeguarding each of the system track relays TR and KR against false response due to inductive "kick back" energy that may be generated in the track rails at the end of each of the energy pulses that is applied at the relay location. Location VII's relay KR2 will serve to illustrate. With respect to it the possibility of false "kick back" response occurs each time that device CT1's contact 5 disconnects source TB1 from track section VIa—VII's rails 1—2.

Due to the inductive properties of those rails plus the conductance of the rail separating ballast, such disconnection is accompanied by a tendency for "kick back" current to continue to flow in the rails in the same direction as source TB1 produced while coding contact 5 was picked up. Upon that contact's release, therefore, this "kick back" current may falsely pick up track relay KR2 over a path extending from rail 2 through conductor 11, the KR2 winding, conductor 28, CT1's back contact 5, and conductors 9—10 back to rail 1.

For preventing such false pick-up on the part of each of Fig. 10's track relays KR2—TR1—KR1—TR2, I include in the rail-connecting circuit for each relay a reactor 29 which corresponds to and performs the same functions as the similarly identified element in each of Figs. 1, 3, 5 and 8. Here, as in those earlier figures, reactor 29 establishes for the track relay winding a connection through which each pulse of rail energy applied at the relay location flows current through the relay winding in the non-pick-up direction.

In the case of location VII's relay KR2, the path for this current flow extends from the positive terminal of source TB1 through impedance 8, CT1's front contact 5, conductor 9, reactor 29, the winding of relay KR2 and conductor 12 back to the negative terminal of source TB1. While ineffective for picking up relay KR2, this right-to-left flowing current builds up in the relay winding and in the reactor a magnetic flux by which an energy of self inductance is later generated.

Upon the subsequent release of location VII's coding contact 5: (1) the section rails 1—2 tend to flow through the winding of relay KR2 a "kick back" current in the direction of from left to right; and (2) the then generated energy of self inductance in relay KR2's winding and in reactor 29 tends to continue the flow therethrough of current in the opposite or right-to-left direction. These currents directly oppose each other and by choosing the magnitude of the winding's plus reactor's kick back current to slightly exceed that generated in the rails, relay KR2 is effectively held released following each disconnection from the rails of trackway source TB1.

In the case of each of the remaining track relays in the Fig. 10 system, the associated impedance 29 guarantees similar immunity to false pick-up by rail "kick back" energy. Because of

the obvious identity of the immunity producing structures and operations no further discussion of these remaining impediments is deemed necessary.

Summary

Although the several improvements of my invention have been shown and described as forming parts of "coded" control circuits of the track type, it will be obvious that these improvements are not restricted to track circuits but that they also have utility when applied to control circuit combinations of any other form wherein the conductors lose their normal energy transmitting capability under certain conditions only.

Thus, instead of being track rails as shown, the control circuit conductors 1-2 may also take the form of line wires which connect master energy supply and feed back receiving equipment (see devices TB-CR-KR at location III in each of Figs. 1, 4, 5, 7, 8, 9) at one end of the circuit with master energy receiving and feed back energy supply equipment (see devices TR-IR-KB at location II in each of Figs. 1, 3, 5, 8) at the other end of the circuit.

When used in control circuits of the line conductor type just described, each of the improvements herein disclosed will function in exactly the same manner as when used with the track type of control circuits that are herein illustrated. My invention is, therefore, one of broad utility and is not restricted to the specific forms of application that I have shown by way of illustration.

From the foregoing description of Figs. 1 to 10, therefore, it will be seen that I have made important contributions to control circuit combinations of the "coded feed back" class. In particular, I have increased the utility and broadened the range of application of "coded feed back" control circuits of both the track and the line type; I have organized the apparatus elements of such circuits in a new and improved manner that is alternative to the organization which assignee's Patent No. 2,286,002 to Frank H. Nicholson discloses and claims; I have provided for such "coded feed back" control circuits a design wherein the "storage potential" plus "bridging contact" protection features of the aforesaid Nicholson form of organization are supplemented by further desirable characteristics not heretofore attainable; I have rendered both the "feed back" and the "master code" relays of such circuits highly immune to false operation by "foreign" and "inductive kick back" currents that may be present in the circuit conductors; and I have provided for direct current track circuits of the "frequency code" signaling system type an improved "feed back" design which permits alternating current energy for cab signal control to be superimposed upon the direct current "master" energy pulses over a supply path which need not include the "feed back" detector relay's operating winding.

Although I have herein shown and described only a few forms of coded control circuits which embody my invention, it is understood that various changes and modifications may be made therein within the scope of the appended claims without departing from the spirit and scope of my invention.

Having thus described my invention, what I claim is:

1. In combination, a section of track that includes first and second traffic rails, means at the

exit end of said section for supplying said section rails with master code energy in the form of recurring "on" period pulses that are separated by "off" period intervals and that are of a given polarity which makes said first rail positive with respect to said second, means located at the entrance end of said section and operated by the there received pulses of said master code energy for further supplying said rails with pulses of

10 feed back energy that recur in step with said master code "off" periods and that are of an opposite polarity which makes said second rail positive with respect to said first, a code following detector relay at said section's exit end connected across said rails and having a contact which responds to each rail-supplied pulse of said given polarity master code energy by moving to a first position and which responds to each rail-transmitted pulse of said opposite polarity feed back energy by moving to a second position, and traffic governing apparatus controlled by said detector relay contact and distinctively responsive according as that contact is or is not repeatedly shifted between its said first and second positions.

2. In combination, a section of track that includes first and second traffic rails, means including a coding contact at the exit end of said section for supplying said section rails with master code energy in the form of recurring pulses that are of a given polarity which makes said first rail positive with respect to said second, means located at the entrance end of said section and operated by the there received pulses of said master code energy for further supplying said rails with

25 pulses of feed back energy that recur in step with said master code "off" periods and that are of an opposite polarity which makes said second rail positive with respect to said first, a code following detector relay at said section's exit end having an operating winding which is connected in parallel with said rails and being provided with a contact which responds to each winding-received pulse of said given polarity master code energy by moving to a first position and which

30 responds to each winding-received pulse of said opposite polarity feed back energy by moving to a second position, an impedance serially included in said connection to limit the flow through said relay winding of current that is due to said "on" period pulses of master code energy, means governed by said coding contact for bypassing said impedance during said master code "off" periods whereby to render it ineffective during received pulses of said feed back energy, and traffic governing apparatus controlled by said detector relay contact and distinctively responsive according as that contact is or is not being repeatedly shifted between its said first and second positions.

3. In combination, a control circuit that includes first and second conductors which normally are capable of transmitting energy between given and opposite ends of the circuit but which at times are rendered incapable of such transmission, means at the given end of said circuit

35 for supplying said conductors with master code energy in the form of recurring "on" period pulses that are separated by "off" period intervals and that are of a positive polarity which makes said first conductor positive with respect to said second, means located at the opposite end of said circuit and operated by the there received pulses of said master code energy for further supplying said conductors with pulses of feed

40 back energy that recur in step with said master code "off" periods and that are of a negative po-

larity which makes said second conductor positive with respect to said first, a code following detector relay at said given circuit end connected in energy receiving relation with said conductors and having a contact which responds to each of said conductor-supplied pulses of positive polarity master code energy by moving to a first position and which responds to each of said conductor-transmitted pulses of negative polarity feed back energy by moving to a second position, and signaling apparatus controlled by said detector relay contact and distinctively responsive according as that contact is or is not being repeatedly shifted between its said first and second positions.

4. In combination, a control circuit that includes first and second conductors which normally are capable of transmitting energy between given and opposite ends of the circuit but which at times are rendered incapable of such transmission, means at the given end of said circuit for supplying said conductors with master code energy in the form of recurring "on" period pulses that are separated by "off" period intervals and that are of a positive polarity which makes said first conductor positive with respect to said second, means located at the opposite end of said circuit and operated by the there received pulses of said master code energy for further supplying said conductors with pulses of feed back energy that recur in step with said master code "off" periods and that are of a negative polarity which makes said second conductor positive with respect to said first, a code following detector relay at said given circuit end having a winding which is connected across said conductors to receive operating energy therefrom and being provided with a contact which responds to each winding-received pulse of said positive polarity master code energy by moving to a first position and which responds to each winding-received pulse of said negative polarity feed back energy by moving to a second position, and signaling apparatus controlled by said detector relay contact and distinctively responsive according as that contact is or is not being repeatedly shifted between its said first and second positions.

5. In combination, a control circuit that includes first and second conductors which normally are capable of transmitting energy between given and opposite ends of the circuit but which at times are rendered incapable of such transmission, means including a coding contact at the given end of said circuit for there supplying said conductors with master code energy in the form of recurring "on" period pulses that are separated by "off" period intervals and that are of a positive polarity which makes said first conductor positive with respect to said second, means located at the opposite end of said circuit and operated by the there received pulses of said master code energy for there further supplying said conductors with pulses of feed back energy that recur in step with said master code "off" periods and that are of a negative polarity which makes said second conductor positive with respect to said first, a code following detector relay at said given circuit end having an operating winding which is connected in parallel with said conductors and being provided with a contact which responds to each winding-received pulse of said positive polarity master code energy by moving to a first position and which responds to each winding-received pulse of said negative polarity feed back energy by moving to a second position,

an impedance serially included in said connection to limit the flow through said relay winding of current that is due to said "on" period pulses of master code energy, means governed by said coding contact for by-passing said impedance during said master code "off" periods whereby to render it ineffective during received pulses of said feed back energy, and signaling apparatus controlled by said detector relay contact and distinctively responsive according as that contact is or is not being repeatedly shifted between its said first and second positions.

6. In combination, a control circuit that includes first and second conductors which normally are capable of transmitting energy between given and opposite ends of the circuit but which at times are rendered incapable of such transmission, means at the given end of said circuit for supplying said conductors with master code energy in the form of recurring "on" period pulses that are separated by "off" period intervals and that are of a positive polarity which makes said first conductor positive with respect to said second, a code following relay at the opposite end of said circuit having a winding which is connected with said conductors and being provided with a contact which responds to each winding-received pulse of said positive polarity master code energy by moving to a picked-up position and which occupies a released position when said winding either fails to receive positive polarity energy or has negative polarity energy impressed thereon, means governed by said relay contact and effective during master energy produced code following operation thereof for further supplying said conductors with feed back energy in the form of pulses that recur in step with said master code "off" periods and that are of said negative polarity which makes said second conductor positive with respect to said first, a code following detector relay at said given circuit end connected in energy receiving relation with said conductors and having a contact which responds to each of said conductor-supplied pulses of positive polarity master code energy by moving to a first position and which responds to each of said conductor-transmitted pulses of negative polarity feed back energy by moving to a second position, and signaling apparatus controlled by said detector relay contact and distinctively responsive according as that contact is or is not being repeatedly shifted between its said first and second positions.

7. In combination, a control circuit that includes first and second conductors which normally are capable of transmitting energy between given and opposite ends of the circuit but which at times are rendered incapable of such transmission, means at the given end of said circuit for supplying said conductors with master code energy in the form of recurring "on" period pulses that are separated by "off" period intervals and that are of a positive polarity which makes said first conductor positive with respect to said second, a code following relay at the opposite end of said circuit having an operating winding which is connected in parallel with said conductors and being provided with a contact which responds to each winding-received pulse of said positive polarity master code energy by moving to a picked-up position and which occupies a released position when said winding either fails to receive positive polarity energy or has negative polarity energy impressed thereon, means including an impulse device governed by said relay

contact and effective during master energy produced code following operation thereof for further supplying said conductors with feed back energy in the form of pulses that recur in step with said master code "off" periods and that are of said negative polarity which makes said second conductor positive with respect to said first, an impedance serially included in said conductor-to-relay winding connection to limit the flow through said winding of current that is due to said "off" period pulses of feed back energy, means governed by said impulse device for bypassing said impedance during each "on" period of the received master code whereby to render it ineffective during each received master code energy pulse, a code following detector relay at said given circuit end connected in energy receiving relation with said conductors and having a contact which responds to each of said conductor-supplied pulses of positive polarity master code energy by moving to a first position and which responds to each of said conductor-transmitted pulses of negative polarity feed back energy by moving to a second position, and signaling apparatus controlled by said detector relay contact and distinctively responsive according as that contact is or is not being repeatedly shifted between its said first and second positions.

8. In a coded railway signaling system, in combination, a section of railway track, a code following track relay having its winding connected across the section rails at one end of the track section, a feed back detector relay at the other end of said track section having one terminal of its winding connected to one terminal of the winding of a reactor, the other terminal of the detector relay winding being connected by a first conductor to one track rail and the other terminal of the reactor winding being connected by a second conductor to the other track rail of said track section, said detector relay being of a type the contacts of which are moved from a first to a second position when and only when energy flows through the relay winding in a given direction, a coding device having a contact continuously actuated between a first and a second position, said coding device contact being effective when in its first position to connect a track battery across said conductors to thereby cause energy to be supplied from said battery to the section rails and to also cause to be supplied to the detector relay winding through the reactor energy which flows through the winding of said detector relay in the reverse of said given direction, the reactor being proportioned so that on interruption of the circuit of the track battery the energy supplied from the reactor to the detector relay prevents operation of the detector relay by energy supplied thereto due to inductive discharge of the track circuit occurring on interruption of the circuit of the track battery, and means associated with the track relay and operative when the coding device contacts are in their second position to supply to the detector relay winding over the track rails feed back energy which flows through the winding of said detector relay in said given direction.

9. In a coded railway signaling system, in combination, a section of railway track, a code following track relay having its winding connected across the section rails at one end of the track section, a feed back detector relay at the other end of the track section having its winding connected across the section rails, said detector relay being of a type the contacts of which are

5 moved from a first to a second position when and only when energy flows through the relay winding in a given direction, a coding device having a contact continuously actuated between a first and a second position, said coding device contact being effective when in its first position to connect a track battery across the section rails and the winding of said detector relay in multiple so that energy from the track battery flows through the 10 winding of said detector relay in the reverse of said given direction, the circuit over which energy is supplied from the track battery to the detector relay being of relatively high inductance so that on interruption of the circuit of the track battery energy continues to flow temporarily in the circuit of the detector relay winding in the reverse of said given direction and is of such magnitude as to prevent operation of the relay by energy supplied thereto due to inductive discharge of the track circuit occurring on interruption of the circuit of the track battery, and means associated with the track relay and operative when the coding device contacts are in their second position to supply to the detector 15 relay winding over the section rails feed back energy which flows through the winding of said detector relay in said given direction.

10. In a coded railway signaling system, in combination, a section of railway track, a code following track relay having its winding connected across the section rails at one end of the track section, a feed back detector relay at the other end of the track section having its winding connected across the section rails, said detector 20 relay being of a type the contacts of which are moved from a first to a second position when and only when energy flows through the relay winding in a given direction, a coding device having a contact continuously actuated between a first and a second position, said coding device contact being effective when in its first position to connect a track battery across the section rails and the winding of said detector relay in multiple so that energy from the track battery flows through the 25 winding of said detector relay in the reverse of said given direction, the circuit over which energy is supplied from the track battery to the detector relay including in series therewith an inductive winding so that on interruption of the circuit of the track battery the inductive discharge from said inductive winding temporarily maintains flow through the detector relay winding in the reverse of said given direction energy of such magnitude as to prevent operation of the relay by energy supplied thereto due to inductive discharge of the track circuit occurring on interruption of the circuit of the track battery, and means associated with the track relay and operative when the coding device contacts are in their second position to supply to the detector relay winding over the track rails feed back energy which flows through the winding of said detector relay in said given direction.

11. In a coded railway signaling system, in combination, a section of railway track having a first and a second track rail, a code following track relay at one end of said track section having its winding connected across the section rails in series with a first reactor with the first terminal of said relay winding connected to said first rail and the second terminal of said relay winding connected to said second rail, said track relay being of a type the contacts of which are moved from a first to a second position when and only 25 when energy flows through the relay winding

from its first to its second terminal, a code following detector relay at the other end of said track section having its winding connected across the section rails in series with a second reactor with the first terminal of said relay winding connected to said first rail and the second terminal of said relay winding connected to said second rail, said detector relay being of a type the contacts of which are moved from a first to a second position when and only when energy flows through the relay winding from its second to its first terminal, a coding device having a contact continuously actuated between a first and a second position, said coding device contact being effective when in its first position to connect a track battery across the section rails in multiple with the detector relay winding and said second reactor with the positive terminal of said battery connected to said first track rail, and means effective on movement of the track relay contacts to their first position to momentarily connect a feed back battery across said section rails in multiple with the winding of said track relay and said first reactor with the positive terminal of said battery connected to said second track rail, each of said reactors being effective on interruption of the supply of energy from the associated battery to momentarily maintain flow of energy through the winding of the associated relay and thereby prevent operation of the relay by energy supplied to the relay due to inductive discharge of the track circuit on interruption of the supply of energy from the battery at that end of the track section.

12. In a coded railway signaling system, in combination, a section of railway track having a first and a second track rail, a code following track relay at one end of the track section having its winding connected across the section rails with the first terminal of said relay winding connected to said first track rail and the second terminal of said relay winding connected to said second track rail, said track relay being of a type the contacts of which are moved from a first to a second position when and only when energy flows through the relay winding from its first to its second terminal, a code following detector relay at the other end of the track section having its winding connected across the section rails with the first terminal of said relay winding connected to said first track rail and the second terminal of said relay winding connected to said second track rail, said detector relay being of a type the contacts of which are moved from a first to a second position when and only when energy flows through the relay winding from its second to its first terminal, a coding device having a contact continuously actuated between a first and a second position, said coding device contact being effective when in its first position to connect a track battery across said section rails in multiple with the winding of said detector relay with the positive terminal of said battery connected to said first track rail, and means operative on movement of the contacts of said track relay to their first position to momentarily connect a feed back battery across said section rails in multiple with the winding of said track relay with the positive terminal of said battery connected to said second track rail, the circuits over which energy is supplied from the track battery to the detector relay winding and from the feed back battery to the track relay being of relatively high inductance so that on interruption of the circuit of the battery associated with each of these re-

lays energy continues to flow temporarily in the circuit of the relay and prevents operation of the relay by energy supplied thereto due to inductive discharge of the track circuit on interruption of the circuit of the battery associated with each of these relays.

13. In a coded railway signaling system, in combination, a section of railway track having a first and a second track rail, a code following track relay at one end of the track section having its winding connected across the section rails with the first terminal of the relay winding connected to the first rail and the second terminal of the relay winding connected to the second rail, said track relay having a contact biased to a released position and movable therefrom to a picked-up position when and only when energy flows through the relay winding from the first to the second terminal thereof, means operative on movement of the contacts of said track relay to their released position to momentarily connect a feed back battery across the section rails and the winding of said track relay in multiple with the positive terminal of the battery connected to the second track rail, the circuit over which energy is supplied from the feed back battery to the track relay being of relatively high inductance so that on interruption of the circuit of the feed back battery energy continues to flow temporarily in the circuit of the track relay winding from the second to the first terminal thereof and is of such magnitude as to prevent operation of the relay by energy supplied thereto due to the inductive discharge of the track circuit occurring on interruption of the circuit of the feed back battery, a feed back detector relay at the other end of the track section, means for connecting the winding of said detector relay across the section rails, and a coding device located at said other end of said track section and having a contact continuously actuated between a first and a second position, said coding device contact being effective when in its first position to connect a track battery across the section rails with the positive terminal of the battery connected to said first track rail.
14. In a coded railway signaling system, in combination, a section of railway track having a first and a second track rail, a code following track relay at one end of said track section having its winding connected across the section rails, a code following detector relay at the other end of said track section having its winding connected across the section rails in series with a reactor, said detector relay being of a type the contacts of which are moved from a first to a second position when and only when energy flows through the relay winding in a given direction, a coding device having a contact continuously actuated between a first and a second position, said contact being effective when in its first position to connect a track battery across the section rails in multiple with said reactor and the detector relay winding in such manner that energy from said track battery flows through the winding of said detector relay in the reverse of said given direction, said reactor being proportioned so that on interruption of the circuit of the track battery energy supplied from the reactor to the detector relay prevents operation of the detector relay by energy supplied thereto due to inductive discharge of the track circuit occurring on interruption of the circuit of the track battery, said coding device contact being effective

when in its second position to establish a circuit independent of said reactor for connecting the detector relay winding across the section rails, and means effective on release of the track relay contacts for momentarily supplying to the detector relay winding over the section rails energy which flows through the winding of said detector relay in said given direction.

15. In a coded railway signaling system, in combination, a section of railway track, a code following track relay at one end of the track section having its winding connected across said section rails, a code following detector relay at the other end of said track section having one terminal of its winding connected by a first conductor to one track rail of said track section and having the other terminal of its winding connected to one terminal of the winding of a reactor the other terminal of which is connected by a second conductor to the other track rail of said track section, said detector relay being of a type the contacts of which are moved from a first to a second position when and only when energy flows through the relay winding in a given direction, a track battery having one of its terminals connected to said first conductor, a coding device having a contact continuously actuated between a first and a second position, said contact being effective when in its first position to connect said second conductor to the other terminal of said track battery and being effective when in its second position to connect said second conductor to said other terminal of said detector relay winding, the track battery being arranged so that energy supplied therefrom through the reactor to the detector relay winding flows through the detector relay winding in the reverse of said given direction, the reactor being proportioned so that on interruption of the circuit of the track battery energy supplied from the reactor to the detector relay prevents operation of the detector relay by energy supplied thereto due to inductive discharge of the track circuit occurring on interruption of the circuit of the track battery, and means effective on release of the track relay contacts for momentarily supplying to the detector relay over the section rails energy which flows through the winding of said detector relay in said given direction.

16. In a coded railway signaling system, in combination, a section of railway track, a code following track relay at one end of the track section having one terminal of its winding connected by a first conductor to one track rail of said track section and having the other terminal of its winding connected to one terminal of a reactor the other terminal of which is connected by a second conductor to the other track rail of said track section, said track relay having a contact biased to a released position and movable therefrom to a picked-up position when and only when energy flows through the relay winding in a given direction, a feed back battery having one of its terminals connected to said first conductor, an impulse relay having a contact biased to a released position in which it connects said second conductor to said other terminal of the track relay winding and movable

therefrom to a picked-up position in which it connects said second conductor to the other terminal of said feed back battery, said feed back battery being arranged so that energy supplied 5 therefrom through the reactor to the track relay winding flows through the track relay winding in the reverse of said given direction, the reactor being proportioned so that on interruption of the circuit of the feed back battery energy supplied from the reactor to the track relay prevents operation of the track relay by energy supplied thereto due to inductive discharge of the track circuit occurring on interruption of the circuit of the feed back battery, means operative 10 on release of the contact of the track relay for momentarily energizing said impulse relay, a detector relay at the other end of said track section operated by energy supplied from said feed back battery over the section rails, and means at said other end of said section for supplying to the track relay over the section rails coded energy of a polarity such that this energy flows through the winding of the track relay in said given direction.

17. In a coded railway signaling system, in combination, a section of railway track through which are operated locomotives equipped with cab signal apparatus responsive to flow of coded alternating current in the section rails, a code following track relay at the entrance end of the section having its winding connected across the section rails, a code following detector relay at the exit end of the section having one terminal of its winding connected by a first conductor to one of the section rails and having the other terminal of its winding connected to one terminal of a reactor the other terminal of which is connected by a second conductor to the other of the section rails, said detector relay being of a type 30 the contacts of which are moved from a first to a second position when and only when energy flows through the relay winding in a given direction, a coding device having a contact continuously actuated between a first position in which it connects the second conductor to the first conductor in series with a track battery and the secondary winding of a track transformer and a second position in which it connects said second conductor to said other terminal of the detector 35 relay winding, the track battery being arranged so that energy supplied therefrom through the reactor to the detector relay winding flows through the detector relay winding in the reverse of said given direction, the reactor being proportioned so that on interruption of the circuit of the track battery energy supplied from the reactor to the detector relay prevents operation of the detector relay by energy supplied thereto due to inductive discharge of the track circuit occurring on interruption of the circuit of the track battery, and means effective on release of the track relay contacts for momentarily supplying to the detector relay over the section rails energy which flows through the winding of said detector relay in said given direction.

HOWARD A. THOMPSON.
